CLAIM

The ornamental design for an electric bike with built-in coffee shop, as shown and described.

DESCRIPTION

1. Electric bike with built-in coffee shop

1.1 : Perspective

1.2 : Left

1.3 : Right

1.4 : Front

1.5 : Back

1.6 : Top

1.7 : Perspective view with open doors

The electric bike with built-in coffee shop; the article consists of a cabin with a frame, pedals, sprocket, chain, steering wheel, and a seat, along with windshield, headlights, and mirrors, and of a compartment with coffee-making equipment; the compartment is split by the tabletop into two parts; the lower part has doors on both sides that open sideways, and the upper part has doors on both sides that open upwards; there are water tanks in the lower part and a coffee machine, milk frother, sink, and shelf in the upper part; the reflections and shadows shown in reproductions are disclaimed.

1 Claim, 7 Drawing Sheets
